UNITED STATES PATENT OFFICE.

JOHN ALLES AND WILLIAM N. FISHER, OF BOSTON, MASSACHUSETTS.

DESIGN FOR A WAGON-BODY.

SPECIFICATION forming part of Design No. 20,999, dated August 18, 1891.

Application filed January 12, 1891. Serial No. 377,558. Term of patent 14 years.

To all whom it may concern:

Be it known that we, JOHN ALLES and WILLIAM N. FISHER, both citizens of the United States, residing at Boston, in the county of Suffolk and State of Massachusetts, have invented and produced a new and original Design for a Wagon-Body, of which the following is a specification, reference being had to the accompanying drawing, forming part thereof.

The figure represents a perspective view of an advertising wagon or carriage embodying our design.

The leading feature of our design consists in the body of the carriage or wagon representing a cigar-box, having an ornamental railing round the top, with a driver's seat in front and a hood over the same.

A represents the body of the carriage or wagon, made to represent a cigar-box. Around 20 the upper portion of the body A is a fancy railing B. The space between the railing and the body is wire-netting C.

E is the driver's seat, and F a hood over the same. 25

What we claim is—

The design for a wagon-body, as herein shown and described.

JOHN ALLES.
WILLIAM N. FISHER.
